CLAIM

The ornamental design for a CT gantry shield, as shown and described.

DESCRIPTION

FIG. 1 is a top plan view of a first embodiment for a CT gantry shield; and,

FIG. 2 is a top plan view of a second embodiment for a CT gantry shield with the same adhesive liner placement design.

(Continued)

The bottom, front, back, left, and right side views of the embodiments form no part of the claimed design.

1 Claim, 2 Drawing Sheets
